SNUBBING DEVICE

Clyde Lemuel Sharpe, Shouldice, Alberta, Canada

Application November 1, 1943, Serial No. 508,591
In Canada November 2, 1942

10 Claims. (Cl. 119—126)

This invention relates to a device for snubbing animals, and particularly cows, while they are being milked.

An object of the present invention is the provision of a device for preventing cows from kicking the pail or the milker when they are being milked.

Another object is the provision of a device for accomplishing this result without interfering with the ordinary movements of the cow while it is being milked.

A further object is the provision of a device adapted to be secured to the hind leg of a cow which will permit ordinary movement of the leg and yet will prevent the cow from kicking with that leg.

A still further object is the provision of a portable device of the nature described which may be moved from stall to stall.

Yet another object is the provision of a snubbing device of simple and inexpensive construction.

With these and other objects in view, the present invention consists essentially of a snubbing device comprising a rotatably mounted drum, a rope secured to and adapted to be wound around the drum, resilient means for normally holding the drum in a position with the rope therearound, said drum rotating as the rope is evenly pulled out and being returned to its normal position by the resilient means when the pull on the rope ceases, and means associated with the drum for preventing the latter from rotating when the rope is subjected to a sharp pull, as more fully described and illustrated by way of example in the following specification and the accompanying drawing, in which

Figure 1 is a plan view of the snubbing device,
Figure 2 is a side elevation thereof, and

Figure 3 is an elevation of the opposite side of the device.

Referring more particularly to the drawing, 10 is a drum rotatably mounted on a shaft 11 which is supported in any suitable manner. This shaft is displaceable in its supporting means. In this example, the supporting means consists of spaced arms 12 and 13 projecting outwardly from a bracket 14 which may be removably or permanently mounted on any suitable support, such as a wall or stand.

The shaft 11 is pivotally mounted at one end on the arm 12 by means of a pivot 15, and its opposite end extends freely through an elongated slot 16 formed in the arm 13. Means is provided for normally holding the shaft against the inner end of the slot 16, that is, the end of the

slot nearest the bracket 14. A spring 17 is provided for this purpose, and one end of said spring is anchored to the bracket while the other end thereof is connected to the free end of the shaft. The outer end of the spring may be connected to an eye-bolt 18 extending freely through the shaft and having a nut 20 threaded on the end thereof. The tension of the spring may be regulated by turning the nut 20.

10 A spring 21 may be mounted on the shaft 11 between the end of the drum 10 and the arm 12, although this is not absolutely necessary.

A compartment 22 is formed within one end of the drum, and a clock spring 23 is mounted in said compartment and surrounds the shaft 11. 15 The inner end of this spring is secured to the shaft at 24 and the other end thereof is fixed to the drum at 25. The spring 23 is normally so loose that it cannot rotate the drum about the shaft.

20 One or more shoulders 26 radiate from the drum 10 at one side thereof in line with but spaced from an obstruction 27 formed on the outer end of the arm 13, which extends outwardly beyond the drum. This obstruction may be formed by bending the end of the arm at substantially right angles thereto, as shown.

25 A rope 28 secured at one end to the drum 10, is adapted to be wound around said drum. The spring 23 forms resilient means for holding the drum in position with the rope therearound. When the drum is in this position, the spring is not under tension.

30 A hook 30 is slidably mounted on the outer or free end of the rope 28 by means of loops 31. A loop 32, see Figure 3, is formed on the outer end of the rope.

In use, the spring 23 normally holds the drum 10 in a position with the rope 28 wound therearound.

35 When the rope is gently pulled outwardly, the drum rotates on the shaft 11 against the tension of the spring. The outer end of the rope is placed around the leg of an animal and placed over the hook 30. The animal may now move its leg back and forth as long as it does it in a gentle manner. When the leg is moved in one direction, it pulls the rope off the drum, rotating the latter against the tension of the spring 23 and when it is moved in the opposite direction, the spring turns the drum to wind the rope back thereon.

40 If the animal starts to kick, thereby pulling the rope sharply, the drum does not rotate fast enough so that the free end of the shaft 11 moves outwardly in the slot 16 against the tension of

the spring 17. This movement causes one of the shoulders 26 to strike the obstruction 27, thus preventing the drum from rotating. This stops the kick before it really gets started. The spring 17 then returns the shaft to its normal position so that the drum is free to rotate again unless another kick is attempted.

While the shaft 11 is shown with a pivot at one end, it is to be understood that an arrangement similar to that at its opposite end may be substituted therefor. In other words, the pivot end of the shaft might extend through an elongated slot in the arm 12 and a spring 17 employed for holding said end against the inner end of the slot. In this case, the entire shaft would move outwardly when the animal attempted to kick.

This invention is designed chiefly for use when a cow is being milked. The rope 28 is secured to the hind leg of the cow next to the milker so that the cow cannot kick either the milk pail or the milker. This device is small and light and it may be moved to positions behind different cows so that only one device would be required for an entire herd.

Various modifications may be made in this invention without departing from the spirit thereof or the scope of the claims, and therefore, the exact forms shown are to be taken as illustrative only and not in a limiting sense, and it is desired that only such limitations shall be placed thereon as are disclosed in the prior art or are set forth in the accompanying claims.

What I claim as my invention is:

1. A snubbing device comprising a shaft, a drum rotatably mounted on the shaft, means for supporting the shaft, said shaft being displaceable in its supporting means, a rope secured to and adapted to be wound around the drum, resilient means for normally holding the drum in a position with the rope therearound, said drum rotating as the rope is evenly pulled out and being returned to its normal position by the resilient means when the pull on the rope ceases, means normally holding the shaft in one position, and means for preventing the drum from rotating when the shaft is displaced by a sharp pull on the rope.

2. A snubbing device comprising a shaft, a drum rotatably mounted on the shaft, means for supporting the shaft, said shaft being displaceable in its supporting means, a rope secured to and adapted to be wound around the drum, resilient means for normally holding the drum in a position with the rope therearound, said drum rotating as the rope is evenly pulled out and being returned to its normal position by the resilient means when the pull on the rope ceases, means normally holding the shaft in one position, an obstruction located adjacent the drum and at least one shoulder radiating from the drum in line with the obstruction, whereby a shoulder strikes the obstruction to prevent the drum from rotating when the shaft is displaced by a sharp pull on the rope.

3. A snubbing device comprising a shaft, a drum rotatably mounted on the shaft, means for supporting the shaft, said shaft being displaceable in its supporting means, a rope secured to and adapted to be wound around the drum, resilient means for normally holding the drum in a position with the rope therearound, said drum rotating as the rope is evenly pulled out and being returned to its normal position by the resilient means when the pull on the rope ceases, spring means normally holding the shaft in one posi-

tion, and means for preventing the drum from rotating when the shaft is displaced by a sharp pull on the rope.

4. A snubbing device comprising a shaft, a drum rotatably mounted on the shaft, means for supporting the shaft, said shaft being displaceable on its supporting means, a rope secured to and adapted to be wound around the drum, resilient means for normally holding the drum in a position with the rope therearound, said drum rotating as the rope is evenly pulled out and being returned to its normal position by the resilient means when the pull on the rope ceases, spring means normally holding the shaft in one position, means for regulating the tension of the spring means, an obstruction located adjacent the drum, and at least one shoulder radiating from the drum in line with the obstruction, whereby a shoulder strikes the obstruction to prevent the drum from rotating when the shaft is displaced by a sharp pull on the rope.

5. A snubbing device comprising a shaft pivotally supported at one end and movably supported at its opposite end, a drum rotatably mounted on the shaft, a rope secured to and adapted to be wound around the drum, resilient means for normally holding the drum in a position with the rope therearound, said drum rotating as the rope is evenly pulled out and being returned to its normal position by the resilient means when the pull on the rope ceases, means normally holding the shaft in one position, and means for preventing the drum from rotating when the shaft is pivoted by a sharp pull on the rope.

6. A snubbing device comprising a shaft pivotally supported at one end and movably supported at its opposite end, a drum rotatably mounted on the shaft, a rope secured to and adapted to be wound around the drum, resilient means for normally holding the drum in a position with the rope therearound, said drum rotating as the rope is evenly pulled out and being returned to its normal position by the resilient means when the pull on the rope ceases, means normally holding the shaft in one position, an obstruction located adjacent the drum and at least one shoulder radiating from the drum in line with the obstruction, whereby a shoulder strikes the obstruction to prevent the drum from rotating when the shaft is pivoted by a sharp pull on the rope.

7. A snubbing device comprising a shaft pivotally supported at one end and movably supported at its opposite end, a drum rotatably mounted on the shaft, a rope secured to and adapted to be wound around the drum, resilient means for normally holding the drum in a position with the rope therearound, said drum rotating as the rope is evenly pulled out and being returned to its normal position by the resilient means when the pull on the rope ceases, a spring connected to the free end of the shaft for holding it in one position, and means for preventing the drum from rotating when the shaft is pivoted against the tension of its spring by a sharp pull on the rope.

8. A snubbing device comprising a shaft pivotally supported at one end and movably supported at its opposite end, a drum rotatably mounted on the shaft, a rope secured to and adapted to be wound around the drum, resilient means for normally holding the drum in a position with the rope therearound, said drum rotating as the rope is evenly pulled out and being returned to its normal position by the resilient means when the pull on the rope ceases, a spring

connected to the free end of the shaft for holding it in one position, means for regulating the tension of said spring, an obstruction located adjacent the drum and at least one shoulder radiating from the drum in line with the obstruction, whereby a shoulder strikes the obstruction to prevent the drum from rotating when the shaft is pivoted against the tension of its spring by a sharp pull on the rope.

9. A snubbing device comprising a rotatably mounted drum, a rope secured to and adapted to be wound around the drum, a clamping arrangement at the outer end of the rope by means of which said rope may be removably secured to the leg of an animal, resilient means for normally holding the drum in a position with the rope therearound, said drum rotating as the rope is evenly pulled out and being returned to its normal position by the resilient means when the pull on the rope ceases, and means associated with

the drum for preventing the latter from rotating when the rope is subjected to a sharp pull.

10. A snubbing device comprising a shaft, a drum rotatably mounted on the shaft, a rope secured to and adapted to be wound around the drum, a hook slidably mounted on the rope adjacent its outer end, a loop formed on the outer end of the rope, said loop being adapted to be placed over the hook after the rope end is placed around the leg of an animal, resilient means for normally holding the drum in a position with the rope therearound, said drum rotating as the rope is evenly pulled out and being returned to its normal position by the resilient means when the pull on the rope ceases, and means associated with the shaft of the drum for preventing the latter from rotating when the rope is subject to a sharp pull.
